UNITED STATES PATENT OFFICE.

HENRY H. GREENSIDE, OF RICHLFIELD, IOWA.

CHURN-COVER.

1,102,043.

Specification of Letters Patent. Patented June 30, 1914.

Application filed April 20, 1912. Serial No. 692,009.

To all whom it may concern:

Be it known that I, HENRY H. GREENSIDE, a citizen of the United States, residing at Richfield, in the county of Fayette and State of Iowa, have invented new and useful Improvements in Churn-Covers, of which the following is a specification.

The invention relates to churns and has for an object to provide a cover therefor for securely closing the opening of the churn.

The invention embodies, among other features, a cover adapted for locking engagement with the churn body, the cover being so arranged relatively to the body that the cover can be easily and quickly secured in locked position and as easily and quickly removed from the churn body.

In the further disclosure of the invention reference is to be had to the accompanying drawings constituting a part of this specification in which similar characters of reference denote corresponding parts in all the views, and in which:

Figure 1 is a side elevation of a churn showing my cover supported in open position; Fig. 2 is a plan view of the churn showing the cover in closed position; Fig. 3 is a vertical sectional view taken on the line 3—3 in Fig. 2; Fig. 4 is a fragmentary perspective view showing the grooves in the cover frame; and Fig. 5 is a fragmentary perspective view of the cover, showing the locking members formed thereon.

Referring more particularly to the views, I employ a churn body 10 of any preferred type, the said churn body having a top 11 provided with the usual opening 12. A cover frame 13 is rigidly secured to the top 11 by means of suitable bolts 14, the mentioned cover frame being substantially circular in shape and provided with an integral, circular lip 15 depending in the opening 12, the lower end of the mentioned lip being curved inwardly to form a seat 16 for a packing 17, as shown.

A cover 18 is provided to close the opening 12, and the mentioned cover comprises a body portion 19, preferably made of wood, a locking frame 20 being rigidly secured to the body portion 19 by suitable bolts 21, the mentioned locking frame being circular in shape and having formed therewith a depending circular lip 22 having the lower edge thereof beveled and adapted to engage the packing 17, the mentioned depending

lip 22 being arranged to encircle the periphery of the body portion 19 as shown.

A series of inclined grooves 23 are formed on the cover frame 13 adjacent the upper end of the lip 15 and a series of locking lugs 24 are formed on the locking frame 20 adjacent the upper end of the lip 22, the mentioned locking lugs being inclined and adapted to fit into the grooves 23 in the cover frame when it is desired to secure the cover 18 in locked position on the churn body 10.

An integral apertured supporting flange 25 is formed on the cover frame 13 and secured to the cover 18 and to the locking frame 20 thereof is a handle 26 having the ends thereof bent upwardly to form gripping members 27, one of the said gripping members being adapted to extend through the aperture in the supporting flange 25 as shown in Fig. 1, when it is desired to support the cover on the churn body 10 but above the opening 12.

In the use of my device, when it is desired to close the opening 12 of the churn body 10, the cover 18 is mounted over the opening with the locking lugs 24 arranged to register with the grooves 23 formed in the cover frame 13 and then by grasping the gripping members 27 of the handle 26 and imparting a rotating movement to the cover 18, the locking lugs 24 will be advanced in the grooves 23, thus moving the cover downwardly to close the opening 12 of the churn body 10 when the cover is rotated as mentioned, and the mentioned downward movement of the cover will cause the lower beveled edge of the lip 22 to engage the packing 17 mounted upon the seat 16 of the lip 15, thus securely wedging the cover against the packing, thus entirely closing the opening 12 of the churn body 10, it being understood that the cover need only be subjected to a half turn in order to secure the cover in lowered position on the churn body, in view of the arrangement of the grooves 23 and the locking lugs 24 operable in the grooves 23 of the cover frame 13.

It will be observed that the flange 25 is disposed at an angle to the plane of the body portion of the frame 2, as shown in Fig. 1. Therefore, when one of the gripping members 27 is inserted through the opening in the flange 25 the body portion of the cover will be held at an angle with re-

lation to the top 11, so that when the cover is in this position any milk or cream which might be upon the same will have a tendency to gravitate or run therefrom.

Having thus described my invention, I claim:

In combination with a churn top having an opening, a frame including an integral depending portion projecting into the opening and an annular portion lying upon and secured to the churn top, with the said depending portion threaded, a cover having a threaded portion for engagement with the threaded depending portion of the frame and adapted to close the opening of the churn top, an apertured flange formed with

the frame and projecting at an acute angle with relation to the said top, and a handle projecting from an edge of the cover and adapted to pass through the aperture of 20 the flange and abut against the churn top whereby the said cover can be held in an elevated position relatively to the churn top and supported in open position by the said frame.

In testimony whereof I affix my signature in presence of two witnesses.

HENRY H. GREENSIDE.
